ATTACHMENT FOR SCREW DRIVERS

Filed Aug. 28, 1928

INVENTOR.
CHARLES W. BRONK.

BY *Philip S. Hopkins*
ATTORNEY

UNITED STATES PATENT OFFICE

CHARLES W. BRONK, OF BINGHAMTON, NEW YORK

ATTACHMENT FOR SCREW DRIVERS

Application filed August 28, 1928. Serial No. 302,537.

My invention relates to an attachment for screw drivers and has for its primary object the provision of a clamping arrangement adapted to rigidly clamp and hold a screw or bolt in position for turning by the screw driver.

Another object of my invention is to provide a two piece ferrule or clamp provided with means at the heel thereof to normally cause the jaws of the clamp to spread for the insertion of the screw or bolt, at the opposite end thereof.

A further object is to provide a resilient clamping means for the jaws of the ferrule which is easily and readily slidable to and from clamping position.

Still another object is to provide a clamping device of this character which is quickly or easily attached or detached with respect to any standard screw driver, and which by its two part construction permits the insertion of the screw or bolts either through the sides or ends of the clamping device.

Still another object of my invention is to provide such a clamp which will hold the screw driver in the screw slot of the screw and also permits the screw driver to turn in the jaws to locate the slot in the screw head.

Another object is to provide means at the heel of the clamp whereby when the clamping device is released, the jaws of the clamp will automatically open to permit the removal of the screw driver from the screw or the insertion of the screw therein.

A still further object is to provide means at the heel of the clamping device whereby to hold the jaws of such device together and prevent their coming apart and dropping off the screw driver.

Still another object is to provide a separate means whereby the screw driver may be prevented from turning within the jaws of the clamp, thereby rendering the clamping device effective for bolts as well as screws.

As is well known in the carpenter, electric and mechanical trades, it is often necessary or desirable to position a screw or bolt for turning into a part, within a very small radius, insufficient to permit the insertion of a hand to hold the screw or bolt while starting. My

invention provides a means for eliminating the difficulties incident to such conditions and enables the user to not only place the screw or bolt for turning in places difficult to reach, but also securely holds the screw or bolt on the screw driver while the same is being attached. The rigidity with which my improved clamping device holds the screw or bolt on the screw driver, also eliminates the necessity of first drilling or punching a hole to receive the same. Endwise pressure upon the screw driver without displacement of the screw is entirely practical and possible.

Other objects and advantages in details of construction and arrangement of parts will be apparent as the description now proceeds reference being had to the figures of the accompanying drawing wherein like reference numerals indicate like parts.

In the drawing:—

Figure 1 is a side view of a screw driver provided with my attachment.

Figure 2 is a detail cross sectional view illustrating clearly the attachment in use in connection with a screw.

Figure 3 is a detail view illustrating the applicability of my improved attachment for holding a bolt on the end of the screw driver.

Figure 4 is a detail perspective view showing the means for preventing the turning of the screw driver within the clamping device when used for holding and clamping a bolt.

Figure 5 is a detail view showing the clamping jaws in open position.

The reference numeral 1 refers to the handle of a screw driver, having the shank 2, and the flat end 3 for engaging within the screw slot in the head of a screw 4. I have illustrated a standard type of screw driver but it will be understood that my attachment is equally applicable to the ratchet or other types as well. Also there is no limitation placed upon my attachment invention with regards to size of the screw driver with which it is used.

My improved attachment comprises the two clamping jaws 5 which are duplicates and are interchangeable. These jaws 5 are provided at their outer ends with sloping clamping portions 6 adapted to receive and engage the

screw 4 to hold it securely in position as shown in Figures 1 and 2. The jaws 5 are cut away adjacent these clamping portions 6 as at 7 to provide resiliency in such clamping portions and also to provide openings through which the screw 4 may be inserted from the side of the clamp if desired. It will be noted that the lower end of the cut away portion 7 is enlarged as at 8 to permit the insertion of the head of the screw or bolt therethrough. Obviously, also, when the jaws are spread apart, it will be seen that the screw may be inserted therebetween from the end.

Extending in the opposite direction, the jaws 5 have their sides sloping inwardly as at 9 and at a point adjacent the lower end or heel of the jaws, the same are crimped inwardly as at 10, causing the extreme end thereof to flare outwardly as at 11. The ends of these flared portions 11 are provided with a laterally extending burr or flange spun or otherwise suitably provided thereon as shown at 12. A light coil spring 13 is adapted to encircle the jaws at the heel portion thereof, and preferably is screwed or otherwise attached upon the burr or flange member 12 whereby such spring is retained in position. By virtue of this spring 13 and the crimp 10 in the jaws, it will be clear that the function of the spring is normally to force the upper end 6 of the jaws apart. It will be noted here that the flared portions 11 of the clamp are provided with tongue and notch connections as at 14 to prevent relative longitudinal movement between the jaw members 5.

Encircling the outer side of the jaw members 5 is a resilient clamping member 15 in the form of a short coil of flat spring material, adapted to slide downwardly upon the sloping portions 9 of the jaws whereby to permit the coil spring 13 to spread the ends 6 of the jaws apart to receive the screw 4. When the screw driver has been inserted within the slot in the head of the screw 4, however, the clamping member 15 may be slid upwardly and around the enlarged portion of the jaws 5, whereby the clamping portions 6 of the jaws will be securely drawn against the screw 4 to rigidly hold it in position with respect to the screw driver.

Attention is called to another feature and function of the flared ends 11 and the coil spring 13, namely that of preventing the clamping member 15 slipping over the end of the jaws 5 and permitting them to fall apart. The jaws are thus always maintained in operative relation to each other.

If it is desired to use the clamping device for holding a bolt instead of a screw, a simple expedient is applicable to the structure just described to prevent the turning of the screw driver within the clamping jaws. This is shown clearly in Figures 3 and 4 and comprises a clip 16, comprising two flat strips 17 secured together at their ends as at 18, and

spread apart between their ends as at 19 to provide an opening to receive the ends 3 of the screw driver. The length of the clip 16 is such that its ends will project beyond the adjacent edges of the clamping jaws through the cut out portions 7.

Obviously therefore, when a bolt 20 is positioned within the clamping device as shown in Figure 3, with the head 21 thereof resting against the end of the screw driver 3, and against the upper edge of the clip 16, and the resilient clamping member 15 is moved upwardly to clamping position, it will be clear that the bolt 20 is securely clamped between the jaws 5 by the clamping portions 6 thereof and that rotation of the screw driver with relation to the bolt 20 is prevented by means of the clip 16 projecting out through the cut out portions 7, whereby the bolt 20 may be readily turned by the screw driver. The release of the bolt 20 is effected in the same manner as the release of the screw 4, namely, by sliding the resilient clamping member 15 downwardly over the sloping sides 9 of the jaw, whereupon the coil spring 13 tends to spread such jaws at their upper ends and permit the removal of the bolt 20 either through the sides or through the ends thereof.

Obviously, changes may be made in details of construction and arrangement of parts without departing from the spirit and scope of the invention. I do not limit myself, therefore, to the exact structure herein shown and described, other than by the appended claims.

I claim:

1. An attachment for screw drivers comprising a pair of complementary and interchangeable clamping jaws adapted to encircle the screw driver and provided with a crimp intermediate their ends forming pivot means therefor, and resilient means encircling said clamping jaws and adapted to be moved to force said jaws toward each other at one end.

2. An attachment for screw drivers comprising a pair of complementary and interchangeable clamping jaws adapted to encircle the screw driver and provided with a crimp intermediate their ends forming pivot means therefor, and resilient means encircling said jaws and tending to force them toward each other at one end and means on said jaws preventing relative longitudinal movement between said jaws.

3. An attachment for screw drivers comprising a pair of clamping jaws crimped intermediate their ends to form a pivot, the heels of said jaws being flared outwardly and provided with flanges, a coil spring encircling said heels and engaging said flanges, a resilient clamping device encircling and slidably on said jaws for forcing the opposite ends thereof to clamping position, said flanges and spring retaining said clamping device on said jaws.

4. An attachment for screw drivers com-

prising a pair of clamping jaws crimped intermediate their ends to form a pivot, the heels of said jaws being flared outwardly and provided with flanges, a coil spring encircling said heels and engaging said flanges,
5 a resilient clamping device encircling and slideable on said jaws for forcing the opposite ends thereof to clamping position, said flanges and spring retaining said clamping device on said jaws, said clamping device
10 comprising a coil of flat spring material.

5. An attachment for screw drivers comprising a pair of clamping jaws encircling said screw drivers and provided with clamping means for forcing said jaws toward each
15 other at one end to engage and hold a screw or bolt, said jaws being cut away at their sides adjacent such end, and a clip engageable on the end of said screw driver and extending laterally thru said cut away portions where-
20 by said screw driver is prevented from turning relative to said jaws.

In testimony whereof, I affix my signature.
CHARLES W. BRONK.
